(57) **CLAIM**

The ornamental design for a ceiling mount LED notification strobe, as shown and described.

DESCRIPTION

FIG. 1 is a front perspective view of a first embodiment of ceiling mount LED notification strobe showing our new design with internal horn;

FIG. 2 is top plan view thereof;

FIG. 3 is a bottom plan view thereof;

FIG. 4 is a rear elevational view thereof;

FIG. 5 is a front elevational view thereof;

FIG. 6 is a right side view thereof; and

FIG. 7 is a left side view thereof;

FIG. 8 is a front perspective view of a second embodiment of ceiling mount LED notification strobe showing our new design;

FIG. 9 is a top plan view of the embodiment of FIG. 8;

FIG. 10 is a bottom plan view of the embodiment of FIG. 8;

FIG. 11 is a front elevational view of the embodiment of FIG. 8;

FIG. 12 is a rear elevational view of the embodiment of FIG. 8;

FIG. 13 is a right side view of the embodiment of FIG. 8; and,

FIG. 14 is a left side view of the embodiment of FIG. 8.

The portion of the drawing shown in dotted line form no part of the claimed invention.

1 Claim, 8 Drawing Sheets
